VENTILATING SKYLIGHT
Herbert J. Atkinson, % Sudbury Laboratory,
Sudbury, Mass. 01776
Filed Apr. 13, 1965, Ser. No. 447,789
1 Claim. (Cl. 98—37)

This invention represents an improvement on the invention disclosed in my United States Patent 2,711,126, dated June 26, 1955, and the objects of the invention are broadly the same with the exception that the present construction provides for more efficient action in keeping water out of the air flow opening in the bottom plate and in particular allowing water within the dome of the skylight to flow by gravity out at all sides thereof, i.e., around 360° of the skylight, rather than at a few widely spaced drains.

Another object of the invention resides in the provision of making the entire ventilating skylight of only two pieces of molded or cast material which are very easy to install.

The objects of the invention are carried out in general by providing a substantially flat bottom plate with ventilating air opening in it, the plate being attached to the deck or other surface at an opening therein, and a dome element with a corresponding edge is adapted to be secured to the plate but in slightly spaced relation therefrom. The entire edge of the combined plate and dome being spaced, water easily flows out at all points along the circumference thereof.

Also, the two parts are provided with new and improved rim portions at the openings thereof, i.e., the opening in the face of the dome and in the base plate, thus more efficiently preventing the entrance of water.

Other objects and advantages of the invention will appear hereinafter.

Reference is to be had to the accompanying drawings in which:

FIG. 1 is a perspective view illustrating the new skylight;

FIG. 2 is a view partly in section therethrough, and
FIG. 3 is a partial bottom plan view.

The novel skylight is made of two main parts of any kind of suitable material such as metal or plastic or the like. The reference numeral 10 indicates the bottom plate which is preferably circular but can be any shape, and is substantially flat except for the air intake extension 12.

The other main part is the dome portion 14 which corresponds in shape to the bottom plate and has a circumferential flange 16 generally coextensive with the edge portion of the plate 10 and which is adapted to be secured thereto.

The plate 10 is provided to completely cover an opening at 18 in a deck, floor, roof, or the like 20. This plate is applied to the hole completely covering the same and waterproofing beading or compound is placed between the two to prevent any leak under the plate 10.

The bottom plate 10 is also provided with the upwardly extending air intake 12 which in this case is shown as preferably elongated and located adjacent the periphery of the plate 10. It has an opening in it as at 22, this opening being surrounded by an inwardly directed rim 24 and comprises in general an upstanding wall which surrounds an opening through the plate. These walls are preferably

2

tapered inwardly slightly as clearly shown in FIG. 2 and terminate in the inwardly directed rim 24 above described.

If desired a pair of doors 26, 26 may be pivoted to the bottom of the plate and latched in position by a bracket 5 28 so as to prevent too great a breeze from blowing through when necessary.

The dome 14 besides the peripheral flange described includes the semi-dome portion 32, the forward substantially diametrical face 34 of which provides for a water and air opening into the dome, and a somewhat slanted, closed front plate portion 36 extending down to a sharper declivity at 38 blending into the peripheral rim 16.

The extreme peripheral edge 40 of the dome is shown to be rounded over and extended slightly downwardly 15 forming a lip. This lip extends slightly beyond the extreme edge 42 of the plate 10. Spacers 44, 44 are applied in any desired manner to space the flange 16 of the dome from the peripheral edge portion of bottom plate 10, and this is conveniently done by providing screws or the 20 like 46 which extend through flange 16, through the spacers 44, through plate 10, and into the deck, but any fasteners desired can be utilized.

The combined air and water will enter the open face 34 of the dome and it is pointed out that the water will flow 25 over the edge 48 and down onto the plate 10, the edge 48 being to the rear of the nearest part of the air opening 12. The accumulated water in the dome will then immediately flow out of the dome, over the extreme edge of the plate, by gravity. Any slight rocking of the vessel 30 will of course alter the inclination of the device which is fixed to the deck, roof, etc. and thus the present ventilating skylight will always be clear of water. The down-turned edge of the dome at 40 tends to aid in preventing the entrance of water in the reverse direction but the main 35 point is that there is a gap circumferentially located with respect to the dome and the plate, this gap being indicated by the reference numeral 50, and this gap of course extends 360° about the entire device.

Therefore it makes no difference at what inclination 40 to the horizontal the new ventilating skylight happens to be positioned, all of the water that enters it will always be drained out almost immediately, but at the same time the draft of air will flow in through the opening in face 34 and through the air intake member 12 into the interior of 45 the boat, etc. to which the ventilator is applied.

Having thus described my invention and the advantages thereof, I do not wish to be limited to the details herein disclosed, otherwise than as set forth in the claim, but what I claim is:

50 A ventilating skylight construction comprising two main members,
one of said members comprising a generally flat plate
adapted to cover an opening, an air intake opening in
55 said plate to one side of the center thereof, and a
wall rising from the plate about the opening,
the other member comprising a dome member having
substantially a one-half portion thereof substantially
60 flat and continuous and located directly over the air
intake opening in the plate, said dome member in-
cluding a semi-dome having a substantially flat face
portion with an opening therein, the flat face por-
tion being located substantially normal to said plate
and closer to the center of the plate than the air in-
take opening, a circumferential flange on said dome
65 member, means securing said flange to the edge por-

tion of said bottom plate, and washers interposed between the flange and bottom plate holding the flange and bottom plate in slightly spaced relation thereto providing a water outlet circumferentially of the skylight, the extreme edge of the flange in the dome member extending outwardly beyond the extreme edge of the bottom plate, and being rounded and extending downwardly slightly toward the edge of the plate, whereby a minimum of water will enter the skylight between the flange and the bottom plate but water in the skylight will run out at all circumferential points thereof.
